[57] CLAIM

The ornamental design for a tape dispenser package, as shown and described.

DESCRIPTION

FIG. 1 is a front perspective view of a tape dispenser package showing our new design;

FIG. 2 is a front elevational view thereof;

FIG. 3 is a top plan view thereof;

FIG. 4 is an elevational view looking from the left of FIG. 2;

FIG. 5 is an elevational view looking from the right of FIG. 2;

FIG. 6 is a bottom plan view; and

FIG. 7 is a rear elevational view, thereof.

The broken lines in FIGS. 1, 2 and 7 represent score lines.

FIG. 1.

FIG. 3.

FIG. 2.

FIG. 4.

FIG. 7.

FIG. 6.

FIG. 5.
